UNITED STATES PATENT OFFICE.

MAX A. REPELOW, OF NEW YORK, N. Y.

CARD-INDEX.

1,105,306.

Specification of Letters Patent. Patented July 28, 1914.

Application filed December 15, 1913. Serial No. 806,722.

To all whom it may concern:

Be it known that I, MAX A. REPELOW, a citizen of the United States, residing at New York, in the county of New York and State of New York, have invented certain new and useful Improvements in Card-Indexes; and I do hereby declare the following to be a full, clear, and exact description of the invention, such as will enable others skilled in the art to which it appertains to make and use the same.

The present invention relates principally to an improved construction and arrangement of hinged cards suitable for card indexes, cloth sample books, photograph albums and many other uses.

It also covers certain forms of container capable of useful combination with my improved cards.

One object of the invention is to provide an arrangement of hinged cards for the purposes above mentioned which shall lie substantially flat and securely over each other in either of two positions, whether normally upright or recumbent.

Another object of my invention is to supply a volume of hinged cards provided with means whereby any desired card may be exposed with the utmost directness, convenience and certainty.

Certain illustrative and preferred embodiments of my invention are shown in the accompanying drawings, wherein—

Figure 1 is a side elevation of a card index suitable for desk use, Fig. 2 is a front elevation of a portion of the same, portions of the selecting tabs being broken away, Fig. 3 is a median longitudinal section of the holder shown in Fig. 1, Fig. 4 is a side elevation of a modified card index and holder, Fig. 5 is a detail in perspective of a group of the selecting tabs, Fig. 6 is an enlarged edge view of two stubs and hinged cards showing the preferred relative thickness of the same, and Figs. 7 and 8 and 9 are edge views of portions of cards showing various forms of tab construction.

My improved card volumes are composed of superposed elements each comprising a card proper and a stub hinged thereto, which latter is preferably thicker than the card proper. The combined length of card and stub in successive elements is substantially uniform throughout the volume, but the stubs increase in length by substantially uniform degrees from one face (front or

back) of the volume to the other. This gradual increase in the proportion of each successive element taken up by the stub portions thereof produces a hinging plane which is inclined to the normal position of the elements, and it is this arrangement which causes the cards proper to lie flat in either of the two positions for which they are destined. My invention covers any means whereby this arrangement of the hinging plane is secured. The excess in thickness preferably possessed by the stubs over the cards proper aids in the better accomplishment of this end. (See Fig. 6.)

In the modification shown in Fig. 1, the normal position of the cards is upright or nearly so, and in Fig. 1, I have shown about half the cards turned down, at 10, to expose the front card of the group remaining upright, at 11. The full length of the cards is not shown in either position in Fig. 1. These cards proper are hinged in any desired manner to the fixed stubs 12, which, as shown, are thicker than the cards proper. This makes it possible for each group of cards, whether turned up or down, to lie in a tapering group; so that there will be no tendency of either group to spring open, such as would be likely to exist if the cards and stubs were of the same thickness.

It will be noted from an inspection of Fig. 6 that there is a tapered air space between the cards next the hinges which disappears at the edge of the cards. This has a function in keeping the cards from springing open when in the raised position, there being a resultant adhesion near the edges, and a freedom of movement next the hinges. It will also be noted that the thin page is secured by a thin hinged member immediately adjoining the thick stub, there being very little clearance space between the leaf and the stub; the result being that there is not a long hinge to bend or get out of order, and the lower ends of the leaf when in the vertical position will rest on the upper edges of the stubs after an inappreciable downward movement of the leaf. This insures the safety of the hinge, protects the same from wear, and at the same time facilitates the operation of the device. While any suitable hinge may be used, I prefer to employ a thin strong strip 13 firmly pasted along the meeting edges of each card and its stub. (See Fig. 2.)

The upright form shown in Figs. 1, 2 and

3 may be employed as a paper weight, and the preferred form of holder comprises a hollow sheet metal base 14 provided with a partition 15 turned downward and then forward to form a rear chamber inclosing a suitable weight 16, and to provide a stop lip 17. Between the two upright sides of the base, which project forward from the weight 16, the card carriage 18 is mounted, and this mounting is preferably accomplished by providing a supporting or pivoting shaft 19 secured by thumb screws 20 on the two sides of the base 14. The bottom of the carriage 18 is extended backward to form a rib 21 which plays between the floor of the base 14 and the stop lip 17, as the carriage is tilted forward or backward on its pivot 19. This rib is made of metal which can be easily bent more or less, so as to regulate the extent to which the carriage may be tilted forward or backward. The stubs 12 are tightly bound between the back plate 22 of the carriage and a front clamping plate 23; the necessary pressure being provided by the rod 24 which passes through said plates and through suitable apertures in the stubs. The ends of this rod are threaded, and milled nuts 25, 26 are employed to compress the plates against the stubs. This arrangement makes it easy to replace or rearrange the cards.

It is important that the stubs be held in such a manner that they can neither rotate nor slip materially nor be lifted with the retaining rod 24. To prevent lateral twist each stub has an extension which fits snugly between the thin sides of the tilting carriage 18, as clearly shown in Fig. 1, and the pressure exerted by these sides upon the stubs can be regulated by the thumb screws 20. The lifting of the rod 24 is absolutely prevented by the shoulders 23^a on the clamping plate 23, which fit snugly under the extensions 18^a on the sides of the carriage 18.

The dotted lines in Fig. 3 indicate the two positions which the carriage 18 may take around its pivotal support 19, according to the position of the center of gravity of the total card group, as determined by the positions of the cards. I have found that, by providing a tilting carriage of this character, the flat positioning of the cards in proper contact with each other is facilitated. It will be seen that a limited play between the card carrier and the support is permitted when the turned down cards are accidentally pressed down by the hand of the user, as frequently happens in the use of a device of this character. Hard pressure of the hand of the user would not only tend to tear the hinge of the top card, but might also topple the whole holder over forward, causing all the cards to topple forward, whereas this slight yielding of the horizontal cards will serve as a check to prevent

such toppling motion. I have found it important to employ at the front of the group of stubs, a short guard stub 27, extending up to the hinging line of the front card as shown in Figs. 1 and 4. This guard stub acts to prevent the breaking down of the hinge and the pulling off of the hinging strip 13 by the sagging forward of the front card. In order to facilitate exposing at once any desired card without difficulty I supply on one or both edges of the cards a series of selecting tabs. As shown in Fig. 3 these are identified by letters of the alphabet, but, of course, any appropriate identifying marks or characters may be adopted, according to the particular use to which the cards are put.

The selecting tabs are arranged in groups, as for instance the groups G H, I J, or K L, shown in Fig. 3; and each group is displaced longitudinally of the cards with respect to the other groups. As shown with particular relation to the group G H, partly broken away in Fig. 2, the individual tabs 28, 29 and 30 of each group are successively shorter, each than the one in front of it in the same group. This shortening may take place from right to left, as in Fig. 2, or in the other dimension of each tab, as in Fig. 5, or both differences may exist. The essential point, in this connection, is that each tab should project in some direction beyond the edge of the tab behind it. This arrangement makes it possible instantly to select, by feeling with the finger tip, the exact point in the card group where the same is to be opened in order to expose the desired card. Also all necessity of awkward fumbling with the card edges is obviated.

In Fig. 4 is shown a modification of my device wherein the normal position of the cards is substantially horizontal. Here the stubs 12 and guard stub 27 are clamped between the supporting bed 31 and the plate 32, by means of the nuts 33, 34, threaded onto the rod 35. The plate 32 is preferably provided with a downward extension 36 to protect the stub ends, and the other end of said plate is turned upward to form a back support 37 for the cards when they are turned up during use, as shown in dotted lines. The upturned metal sides of the supporting bed 31 fit snugly against the sides of the stubs, to prevent lateral twist or slip therof. Here again, the hinging plane is inclined to the bed 31. This bed is preferably supported at one end by a down-turned portion 38, and at the other end by a similar portion 39 provided with a roller 40, to facilitate moving the whole device over a desk or table. The selecting tabs, in this form as in the other, are arranged in groups, displaced longitudinally.

Fig. 5 shows the arrangement of the tabs in the individual groups; the front tab of

- each group projecting outwardly beyond the next tab to the rear, while the latter tab has a greater length in a longitudinal direction. The projection of tab 41, for instance, beyond 42 in a longitudinal direction facilitates the lifting of the former away from the latter to swing it into the upright position; while, on the other hand, the card 42 projects laterally beyond 41, to facilitate 10 swinging the latter downward again when desired. In this manner selection of cards, either for swinging downward or upward, is readily accomplished. It will be readily understood that, even though there may be 15 no projection of one tab beyond another in a group while the cards are in one position (upright or recumbent) the peculiar hinging described will cause the tabs to be longitudinally displaced with respect to each 20 other when the cards are turned down (or up) into the other position. My invention covers this mode of causing successive tabs to lap over for facilitating manipulation. The tabs may be made in a single piece with 25 the cards as shown in Fig. 5, but it is preferred to provide reinforcement for the same. In Fig. 7 the card is shown at 10, the tab at 41, and a reinforcement 43 on each side of said tab. In Fig. 8 a single reinforcing piece 44 is applied, which is relatively thicker than the card. In Fig. 9, 30 the entire tab 45 is applied directly to the card 10. All of these forms are within my invention.
- 35 Various changes may be made in my improved device without departing from my invention, and I do not limit myself to the details herein shown and described.
- What I claim is—
- 40 1. A device of the class described comprising a group of contiguous flat elements each composed of a thick stub and a relatively thin card hinged thereto, the stub on each successive element being shorter than 45 that on the element next in rear thereof, binding means for holding said stubs together, and means for holding said cards in a position slightly inclined backward from the vertical, substantially as described.
- 50 2. A device of the class described comprising a group of contiguous flat elements each composed of a thick stub and a relatively thin card hinged thereto by a close jointed hinge, the stub on each successive 55 element being shorter than that on the element next in rear thereof, binding means for holding said stubs together, and means for holding said cards in a position slightly inclined backward from the vertical, substantially as described.
- 60 3. A device of the class described comprising a group of contiguous flat elements each composed of a thick stub and a relatively thin card hinged thereto, the stub on 65 each successive element being shorter than
- that on the element next in rear thereof, a guard stub in front of the other stubs, binding means for holding said stubs together, and means for holding said cards in a position slightly inclined backward from the vertical, substantially as described. 70
4. A device of the class described comprising a group of contiguous flat elements each composed of a thick stub and a relatively thin card hinged thereto by a close jointed hinge, the stub on each successive element being shorter than that on the element next in rear thereof, a guard stub in front of the other stubs, binding means for holding said stubs together, and means for holding said cards in a position slightly inclined backward from the vertical, substantially as described. 75
5. A device of the class described comprising a group of contiguous flat elements each composed of a thick stub and a relatively thin card hinged thereto, the stub on each successive element being shorter than that on the element next in rear thereof, binding means for holding said stubs together, said cards being provided individually with tabs arranged in groups disposed longitudinally with respect to the cards, each tab in a group projecting in one direction beyond the edge of the tab behind it, and means for holding said cards in a position slightly inclined backward from the vertical, substantially as described. 80
6. A device of the class described comprising a group of contiguous flat elements each composed of a thick stub and a relatively thin card hinged thereto, the stub on each successive element being shorter than that on the element next in rear thereof, a guard stub in front of the other stubs, binding means for holding said stubs together, said cards being provided individually with tabs arranged in groups disposed longitudinally with respect to the cards, each tab in a group projecting in one direction beyond the edge of the tab behind it, and means for holding said cards in a position slightly inclined backward from the vertical, substantially as described. 85
7. A device of the class described comprising a sheet metal base having a partition bent downward and forward, a weight behind said partition, a tilting carriage on said base having a rib adapted to play under the forward-turned edge of said partition, and a group of cards suitably mounted in said carriage, substantially as described. 90
8. A device of the class described comprising a base, a tilting carriage supported thereon and having a stop rib composed of metal capable of bending readily for purposes of adjustment, a step on said base cooperating with said rib, and a group of cards suitably mounted in said carriage, substantially as described. 95
- 100
- 105
- 110
- 115
- 120
- 125
- 130

- 4
9. A device of the class described comprising a base, a tilting carriage supported thereon, a group of superposed stubs clamped in said carriage and arranged with 5 their outer edges forming a series of steps, and a group of superposed cards hinged individually to the stepped ends of said stubs, substantially as described.
10. A device of the class described comprising a base, a tilting carriage supported thereon, a group of relatively thick stubs clamped in said carriage and arranged with their outer edges forming a series of steps, and a group of superposed relatively thin 15 cards hinged individually to the stepped ends of said stubs, substantially as described.
11. A device of the class described comprising a base having upright sides, a tilting carriage pivoted between said sides, 20 stubs clamped in said carriage and arranged with their outer edges forming a series of steps, and cards individually hinged to the stepped ends of said stubs, 25 substantially as described.
12. A device of the class described comprising a carriage having thin compressible sides, a group of stubs fitting snugly between said sides, means for compressing said sides more or less against said stubs, 30 and cards hinged to said stubs, substantially as described.
13. A device of the class described comprising a group of stubs, a carriage having sides closely confining the edges of said 35 stubs and having forward extensions, a clamping plate having portions engaged by said forward extensions, a securing rod passing through said stubs and clamping plate, and means engaging said rod adapted 40 to exert pressure on said clamping plate, substantially as described.

In testimony whereof, I affix my signature, in presence of two witnesses.

MAX A. REPELOW.
